(57) **CLAIM**

The ornamental design for a lighter tray as shown and described.

DESCRIPTION

FIG. 1 is a perspective view of a lighter tray showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view thereof taken along the line 8-8 of FIG. 6; and,

FIG. 9 is another perspective view thereof with lighters. The broken line in the drawings depict portions of the lighter tray that form no part of the claimed design. The dot-dash-dot broken lines in the drawings represent boundaries of the design and form no part thereof. The broken lines of the lighters in FIG. 9 illustrate unclaimed environment and forms no part of the claimed design.
